UNITED STATES PATENT OFFICE.

JAMES STODDART, OF NEWARK, NEW JERSEY, ASSIGNOR TO THE ENOS COMPANY, OF NEW YORK, N. Y., A CORPORATION OF NEW YORK.

COMBINED LAMP AND SHADE HOLDER.

1,000,452.

Specification of Letters Patent. Patented Aug. 15, 1911.

Application filed May 31, 1911. Serial No. 630,530.

To all whom it may concern:

Be it known that I, JAMES STODDART, a citizen of the United States, residing at Newark, Essex county, State of New Jersey, have invented certain new and useful Improvements in Combined Lamp and Shade Holders, of which the following is a full, clear, and exact description.

My invention relates to improvements in electric lamp fixtures, the object being to provide in a combined lamp and shade a holder so constructed that the holding element may be adjusted so as to permit of the interchange of lamps of different power and size without injuriously affecting the reflection of the light therefrom respectively.

While ordinary incandescent lamps of different power are adapted to a standard socket, said lamps vary so materially in size that an ordinary fixture designed to receive and properly support a large sized lamp will not properly support a small sized lamp. This is due to the fact that the smaller lamp will be, when in place, located at such an elevation that the rays therefrom will not be properly reflected by the shade. By my improvement it is possible to substitute lamps of varying sizes, a simple adjustment being provided whereby, without disturbing the various connections, each particular lamp may be adjusted relatively to the reflector so that they will coöperate to the greatest advantage.

In the accompanying drawings, Figure 1 is a side elevation, partly in section, of my invention adjusted properly to support a comparatively small lamp of relatively low power in proper relation to the shade or reflector. Fig. 2 is a side elevation showing another part in section, said elevation being taken at a plane at right angles to the plane of Fig. 1. Fig. 3 is a detail.

1 represents a link which may constitute the upper support for a combined lamp and shade holder. At the lower part of this link there is a body casting 2, which has a central passage in line with the loop of the link 1. To the lower end of the casting 2 is secured a suitable shade holder frame or bell 3, provided with any suitable means, such as screws, for holding a shade 4.

5 is a lamp socket.

6 is a tube or socket carrier passing through the bore of the casting 2 and taking

into the upper end of the socket 5. The upper end of the tube 6 is provided with an offset 6^a to prevent said tube from moving down to a point beyond a predetermined limit.

7 is a clamp-screw in the casting 2, the forward end of which screw may engage the tube 6 so as to hold it at any desired elevation.

8 represents a lamp adapted to be screwed into the socket 5, said lamp being of comparatively small size and power. When such a lamp is used, the socket 5 is adjusted to stand in a lowered position relatively to the shade support 3 so that the rays from the lamp 8 will be properly reflected.

9 represents, in dotted outline, a larger lamp of relatively higher power. When this lamp is used, it is obvious that in the absence of a relative adjustment between the lamp supporting element and the shade supporting element, said lamp would hang down to such an extent below the desired plane that not only would it be unsightly, but it would not be positioned correctly relatively to the shade 4. To that end, when such a lamp is used, the lamp support or socket 5 may be raised to the position indicated in dotted lines, Fig. 1, said adjustment of the socket being ordinarily accomplished by simply releasing the clamp-screw 7 and pushing the socket up to the proper elevation where the tube 6 may again be gripped by the clamp-screw 7.

The circuit wires which lead into the socket 5 may lead down from above through the tube 6, which latter thereby performs the double function of an adjustable carrier for the socket as well as a guide and protector for the ends of the circuit wires leading into the socket.

By this arrangement very substantial advantages are derived in that a single combined lamp and shade holder may be adapted to various combinations of lamps and shades.

I have shown my invention in its preferred form, but I am aware that various changes may be made without departure from the spirit and scope of the following claims.

If desirable, the flange or offset 6^a may be screw-threaded onto the upper end of the tube 6 whereby it may be applied thereto after the tube 6 has been attached to the

socket and has been passed up through the bore in the body casting 2. To that end it may be assumed that in the drawings a short thread is provided at the upper end 5 of the tube 6 to receive the particular form of flange or offset 6^a therein shown. Indeed, broadly, it is immaterial how the offset 6^a is secured to the tube, although in some instances it is preferable that said 10 flange be arranged to be applied thereto or removed therefrom to facilitate assembling and disassembling of the parts.

What I claim is:

1. In a combined lamp and shade support, a shade carrying element, a lamp socket element, an adjustable connection between said two elements whereby one may be adjusted relatively to the other, said connection including a body casting non-adjustably secured to the shade carrying element, said casting having a bore therein, a tube slidably mounted in said bore, said tube being connected to said lamp socket element and opening into the interior of said element, and means to hold said tube at any position of adjustment in said bore.
2. In a combined lamp and shade sup-

port, a shade carrying element, a lamp socket element, an adjustable connection between said two elements whereby one may be adjusted relatively to the other, said connection including a body casting non-adjustably secured to the shade carrying element, said casting having a bore therein, a tube slidably mounted in said bore, said tube being connected to said lamp socket element and opening into the interior of said element, and means to hold said tube at any position of adjustment in said bore, said means comprising a screw passing transversely through said casting and into the bore to engage the tube therein.

3. In a combined lamp and shade support, a shade supporting element, a lamp supporting socket, a tube leading upwardly from said socket, a guide for said tube, said guide being connected to said shade support, and means to hold said tube at various positions of adjustment in said guide.

JAMES STODDART.
